UNITED STATES PATENT OFFICE.

CLIFFORD G. ARMSTRONG, OF SANDWICH, MASSACHUSETTS.

BROOCH OR THE LIKE.

No. 920,517.

Specification of Letters Patent.

Patented May 4, 1909.

Application filed December 12, 1907. Serial No. 406,168.

To all whom it may concern:

Be it known that I, CLIFFORD G. ARMSTRONG, a citizen of the United States, residing at Sandwich, in the county of Barnstable and State of Massachusetts, have invented a new and useful Improvement in Brooches or the Like, of which the following is a specification.

This invention has reference to an improvement in brooches or pins and more particularly to an improvement in means for securing pin tongue joints and catches to the backs of bar pins, brooches or similar articles of jewelry.

15 The object of my invention is to improve the construction of bar pins, brooches or similar articles of jewelry, whereby the pin tongue joints and catches are more permanently and rigidly secured to the backs of the bar pins or brooches than has heretofore been done, without solder.

20 My invention consists in the peculiar and novel construction of securing pin tongue joints and catches to the backs of bar pins, brooches or similar articles of jewelry, without solder, as will be more fully set forth hereinafter and claimed.

Figure 1 is a back view of a blank forming the body of a bar pin or brooch. Fig. 2 is a back view of the body of a bar pin or brooch, showing the square cavities and raised lips formed on the back of the same by suitable dies. Fig. 3 is a longitudinal sectional view through the body member, 35 showing the cavities and raised lips. Fig. 4 is a sectional view similar to Fig. 3, showing the hinge member of the pin tongue and the catch in the cavities in position to be permanently secured in the same. Fig. 5 is a 40 sectional view similar to Fig. 4, showing the hinge member of the pin tongue and the catch permanently and rigidly secured in the cavities of the body by swaging the end lips over and into the cavities flush with the surface of the back, and Fig. 6 is a transverse sectional view of a modified form, showing a hinge member secured in the cavity by swaging the lips over from the sides.

In the drawings, *a* indicates the solid body

member of a bar pin which may have any design or configuration desired, *b* a hinge member, *c* a pin tongue and *d* a catch member. The solid body member *a* has the two cavities 77 in the back adjacent each end and the oppositely-disposed raised lips 88 at the edges of the cavities, as shown in Figs. 2 and 3. These cavities which may be square, rectangular or any shape other than round, are formed in the back of the body by suitable dies, which force the metal out of the cavities and form the raised lips 88 which may be on the ends or sides of the cavities. The hinge member *b* and catch member *d* are each constructed to have a comparatively narrow 60 neck 9 and an enlarged head 10 shaped to fit in the cavities 77 and having a thickness less than the depth of the cavities, as shown in Fig. 4. The pin tongue *c* is pivotally secured at one end to the hinge member *b*, as shown 70 in Figs. 5 and 6. The hinge member *b* of the pin tongue *c* and the catch member *d* are permanently and rigidly secured to the body *a* by placing the heads 10 10 of the hinge member *b* and the catch member *d* in the cavities 75 77 and, by the use of dies or suitable tools, swaging the lips 88 over the heads 10 10 flush with the surface of the back of the body *a*, as shown in Fig. 5, thereby leaving a smooth finished surface on the back of the 80 pin or brooch.

Having thus described my invention, I claim as new and desire to secure by Letters Patent:—

In a brooch, a metal body member having 85 a cavity therein, and a catch member having a shank with an enlarged head on said shank, the under face of said head seating on the wall formed by the bottom of said cavity, and a pair of lips integral with said body and 90 composed of the metal displaced by the formation of said cavity, said lips seating on the top face of said head.

In testimony whereof I have signed my name to this specification in the presence of 95 two subscribing witnesses.

CLIFFORD G. ARMSTRONG.
Witnesses:

ADA E. HAGERTY,
J. A. MILLER.
